United States Patent

Des. 240,021
Patented May 25, 1976

240,021

STOPPER OR THE LIKE

Creighton M. Lawhead, Corning, N.Y., assignor to Corning Glass Works

Filed Dec. 16, 1974, Ser. No. 532,827

Term of patent 14 years

Int. Cl. D9—07

U.S. Cl. D9—285

Fig. 1

Fig. 2

Fig. 3

Fig. 4

FIG. 1 is a top plan view of a stopper or the like, showing my new design;

FIG. 2 is a side elevational view;

FIG. 3 is a bottom plan view; and

FIG. 4 is a cross-sectional view in elevation taken along line 4—4 of FIG. 1.

I claim:

The ornamental design for a stopper or the like, substantially as shown.
